FISHING LURE

August A. Bruckner, 2324 28th St.,
Lubbock, Tex. 79411

Filed Dec. 4, 1968, Ser. No. 14,789

Term of patent 14 years

Int. Cl. D22—07

U.S. Cl. D22—27

Fig. 1

Fig. 2

Fig. 3

Fig. 4

Fig. 5

FIGURE 1 is a perspective view of a fishing lure showing my new design;

FIGURE 2 is a side elevational view thereof;

FIGURE 3 is a front end view observing FIG. 2 in a direction from right to left;

FIGURE 4 is a bottom plan view; and

FIGURE 5 is a rear end view observing FIG. 2 from left to right.

I claim:

The ornamental design for a fishing lure, as shown.
